UNITED STATES PATENT OFFICE.

WILLIS S. MORSE, OF PHILADELPHIA, PENNSYLVANIA.

REVERSING-SWITCH.

1,103,154.

Specification of Letters Patent.

Patented July 14, 1914.

Application filed November 1, 1912. Serial No. 729,111.

To all whom it may concern:

Be it known that I, WILLIS S. MORSE, a citizen of the United States, residing in Philadelphia, Pennsylvania, have invented certain Improvements in Reversing-Switches, of which the following is a specification.

One object of my invention is to provide a novel form of reversing switch having its parts so arranged that its movable member may be adjusted relatively to an operating member connected to it; the invention contemplating a construction for accomplishing the above results, which is simple, compact, substantial and not likely to get out of order.

I further desire to provide a form of reversing switch having an oscillatory actuating member adjustably connected to its movable contact in order to permit of the distance of said contact from either of two fixed contacts being varied independently of said actuating member.

These objects and other advantageous ends, I secure as hereinafter set forth, reference being had to the accompanying drawings in which:

Figure 1 is a plan partly in section of a reversing switch constructed according to my invention, the cover of the casing being removed; Fig. 2 is a vertical section on the line *a—a*, Fig. 1, Fig. 3 is a fragmentary elevation of a detail of my invention, and Fig. 4 is a plan of a modification of the invention.

In the above drawings, 1 represents an inner closing casing in the form of a box to one side of which is fixed a bearing 2 for an oscillatory spindle 3, constituting the actuating member of the switch. The spindle 3 may be rocked in its bearings 2 by any suitable means (not shown) as for example by a member connected thereto which moves or oscillates in response to changes in the tension of a paper web passing through a printing press or the like. The use of the switch is, however, not confined to printing presses as it is evident that the arrangement is susceptible of more general application.

The switch proper consists of a supporting structure 4 in the form of plate of insulating material mounted within the casing 1 and having fixed to it three brush holders

5, 6 and 7 of rectangular section and respectively provided with binding posts or terminals 8, 9 and 10. These brush holders are mounted on the plate 4 so as to be substantially parallel and have certain of their faces in substantially the same plane; there being a recess or cavity in each of said faces in which is mounted a spring pressed contact or brush 11 preferably made of carbon. Immediately adjacent these contact brushes I slidably mount a block 12 of insulating material such as fiber which is held at a predetermined distance from the ends of the brush holders 5, 6 and 7 by a pair of guides 13 and 14, so formed as to allow it to move longitudinally, while preventing it from moving away from the surface of the plate 4. In a suitable recess in that face of the block 12 engaged by the brushes 11, I mount a metallic plate 15 whose outer face is preferably flush with the adjacent surface of said block and whose length is slightly less than the distance between the two outer-most contact brushes 11, so that when the block 12 is in its mid position its contact plate 15 while electrically engaging the central contact or brush 11 is disengaged from both of the outer contacts 11 although relatively near the same. In order to prevent injury to the plate 15 from arcing, I mount in it adjacent its ends, two supplementary contacts in the form of carbon pieces 16 and 17.

In order to connect the movable switch member formed by the contact plate 15 and the block 12, with the oscillatory spindle 3, I mount on the upper end of this latter an arm 18 and pivot to the end thereof a lever 19, one of whose ends is slotted for the reception of a pin 20 on the block 12 while its other end is similarly slotted for the reception of a pin or projection 21 in the one end of an arm 22. This latter is fixed to a short spindle 23 extending through the plate 24 and having fixed to its outer end a knurled head 25 carrying some form of spring indicator or pointer 26. The plate 24 is provided with a semi-cylindrical series of notches indicated at 27 for the reception of the end of this indicating pointer, whereby it and its associated parts are firmly held in any given position.

Under conditions of use it is obvious that the turning of the spindle 3 through a

small arc in either direction will move the block 12 from the neutral position shown in Fig. 1 into a position in which the contact plate 15 will electrically connect the brushes 11 of one of the brush holders 5 or 7 with the brush of the holder 6, thus so altering the circuit connections of an electric motor connected to the binding posts 8, 9 and 10, as to reverse its direction of rotation. As is well understood, the reversal of the direction of rotation of a motor may be effected by changing the direction of the field flux or by reversing the direction of the current passing through the armature. To reverse the direction of rotation of the motor I prefer to reverse the field flux in the manner shown, described and claimed in my co-pending application, Serial No. 727,955, filed October 26, 1912.

Since it may be desirable to change the relative position of the contact plate 15 with regard to the various brushes without changing the position of the actuating member 3, the head or handle 25 may be turned through any desired angle up to about 90 degrees, thus causing the lever 19 to fulcrum on the pivot 30. The contact plate 15 is thus brought into the desired relative position; and thereafter the operation of the spindle 3 will actuate the block 12 as before, the spring pointer 26 giving indication of the relative adjustment of the arm 18 on either side of its mid position.

The casing or box 1 is usually provided with a cover having a slot for the reception of the pin 20 and the outer end of this latter is preferably formed to co-operate with a fixed index or pointer 31 as shown in Fig. 3, in order to show at a glance the position occupied by the movable switch member 12 and hence whether the motor is connected to the switch for running in one direction or in the other, or is idle. With this idea in view, the fixed index is so placed that when the pin 20 is immediately adjacent it, the contact plate 15 is in its neutral position, disengaged from the brushes of both of the holders 5 and 7.

If desired, I may provide the movable switch member 12 with a plate 15 on each of its two opposite sides or faces and form a double reversing switch by mounting three brush holders 5, 6^a and 7^a with their brushes in position to co-act with the second of said plates 15, as shown in Fig. 4, there being as in Fig. 1, three other brush holders 5, 6 and 7 with their brushes in position to engage the first plate.

I claim:

1. In a switch, the combination with three contacts, of a movable switch member adapted to connect one of said contacts with either of the other contacts, said switch member having a neutral position at which it is in contact with neither of said other

contacts, a member for actuating said switch member, and means for adjusting the position of the switch member relatively to said actuating member.

2. The combination in a reversing switch of a movable member; an oscillatory actuating member; an arm connected to said actuating member; a lever fulcrumed on the arm and connected to the movable switch member; with means independent of said actuating member for turning the lever on its fulcrum.

3. The combination in a reversing switch of a plurality of fixed contacts; a reciprocable member also having a contact; a rotary actuating member; an arm connected to said actuating member; a lever fulcrumed on said arm and pivoted to the reciprocable member; and an adjusting arm also connected to the lever for turning the same relatively to the arm on the rotary actuating member.

4. The combination in a reversing switch of a supporting structure; a plurality of contacts having engaging faces in substantially the same plane; guiding means on the supporting structure; a body of insulating material directed by said guiding means; a contact carried by said body in position to simultaneously engage two of the fixed contacts; a rotary actuating member; an arm thereon; a member pivoted to said arm and also pivoted to said body of insulating material; with means for adjusting said member to vary the relative positions of the contact carried by the body of insulating material and the actuating member.

5. The combination in a reversing switch of fixed and movable contacts; a rotary actuating member; means for adjustably connecting said actuating member and the movable contact of the reversing switch; the same consisting of an adjustable arm supported to rotate on an axis substantially in line with said rotary member; an arm fixed to the rotary member; with a lever fulcrumed on said arm and connected to the adjustable arm and to the movable switch contact.

6. The combination in a reversing switch of a contact mounted to move in a substantially straight line; a rotary actuating member for the switch extending in a line substantially at right angles to the line of movement of said switch member; an adjusting arm mounted to rotate on an axis substantially in line with said actuating member; an arm connected to the actuating member with a member connecting the movable switch contact and the adjusting arm; said member being pivoted to the arm of the actuating member.

7. The combination of a casing; a reversing switch in the casing, including a movable member; an actuating member for the

switch; means for adjustably connecting said actuating member and the movable member; and an indicator actuated by said connecting means to show the position of the movable member.

8. In a reversing switch, the combination with a suitable support, of three consecutive contacts mounted thereon, a switch member adapted to occupy a neutral position out of contact with either of the outer contacts and arranged, when operated, to electrically connect the intermediate contact with either of

the outer contacts, a rockable device for operating said switch member, and adjusting means between said device and the switch member.

In testimony whereof, I have signed my name to this specification, in the presence of two subscribing witnesses.

WILLIS S. MORSE.
